US0D1057752S

(12) **United States Design Patent** (10) **Patent No.:** **US D1,057,752 S**
Ling et al. (45) **Date of Patent:** **** Jan. 14, 2025**

(54) **DISPLAY PANEL OF AN ELECTROPORATION DEVICE WITH A GRAPHICAL USER INTERFACE**

(71) Applicants: **Life Technologies Holdings PTE Ltd**, Singapore (SG); **Life Technologies Corporation**, Carlsbad, CA (US)

(72) Inventors: **Mio Xiu Lu Ling**, Singapore (SG); **Harmon Jr Cosme Sicat**, Singapore (SG); **Joshua Mead**, San Diego, CA (US); **Jia Ni Lim**, Singapore (SG)

(73) Assignees: **Life Technologies Corporation**, Carlsbad, CA (US); **Life Technologies Holdings PTE Ltd.**, Singapore (SG)

(**) Term: **15 Years**

(21) Appl. No.: **29/810,835**

(22) Filed: **Oct. 8, 2021**

(51) LOC (15) Cl. **14-04**

(52) U.S. Cl.

CLAIM

The ornamental design for a display panel of an electroporation device with a graphical user interface, as shown and described.

DESCRIPTION

The sole FIGURE is a front view of a display panel of an electroporation device with a graphical user interface. The outermost broken lines illustrate a display panel or portion thereof and form no part of the claimed design. The remaining broken lines in the drawing showing the graphical user interface form no part of the claimed design.
